UNITED STATES PATENT OFFICE.

JOHN N. POAGE, OF CINCINNATI, OHIO.

WATERING-COLUMN FOR RAILROAD WATER-TANKS.

SPECIFICATION forming part of Letters Patent No. 223,607, dated January 13, 1880.

Application filed December 1, 1879.

To all whom it may concern:

Be it known that I, JOHN N. POAGE, of Cincinnati, Hamilton county, Ohio, have invented a new and useful Improvement in Watering-
5 Columns for Railroad Water-Tanks, of which the following is a specification.

My present invention is in the nature of an improvement upon that for which Letters Patent have been previously granted to me, and
10 particularly Letters Patent No. 217,817, dated July 22, 1879. Said patents describe an improved watering-column for railway use, consisting, essentially, of a vertical column seated in a suitable valve-chamber, and provided with suitable means for keeping its lateral discharge-spout normally in line with the track, and with valves and operating mechanism for controlling the water-supply, and for freeing the stand-pipe as a provision against freezing.
15

20 In the further practical use of said invention it was found that after having used the column for supplying a locomotive and throwing the spout into its normal position, owing to the shortening of the column and the failure of the relief-valve to operate quickly enough, some water remained in the spout, which spilled out upon the ground. This, in freezing weather, was found to be objectionable.

25 30 Again, in the construction and putting together of the apparatus for use, it was found difficult to adjust the column with reference to the valve-seat so as to attain that accuracy absolutely essential to insure a proper fit of the valve upon its seat, or to retain it thereafter, owing to the settling of foundations and wear of parts.

My present invention is designed to remedy these disadvantages; and it consists, first, in a
35 40 relief-valve of peculiar construction, with mechanism for operating the same independently of the vertical play of the column; and, second, in an improved construction of the valve-chamber, and in the mode of connecting the column therewith, whereby the necessary vertical play and any accidental oscillation or defective alignment of the latter are permitted without affecting the valve in relation to its seat.

45 50 The latter feature of my invention, in which the valve-chamber, with the valve, seat, and guide, constitute a separate and distinct struct-

ure from the column, also constitutes an improvement in this respect, whereby the parts are rendered more convenient of transportation and location for use.

55

Figure 1 in the drawings is a sectional elevation of my improved watering-column, with the upper part shown on a reduced scale, showing the main valve on its seat closed, the relief-valve open, and the vertical pipe in its 60 socket; and Fig. 2 is a perspective view of the relief-valve separated from its connections.

F is the valve-chamber, which is cylindrical in its general form, having an inlet-aperture, F', entering its periphery, and the vertical column A coincident with its axis. At the lower side or bottom of the valve-chamber is the seat of the main or supply valve G. I construct this seat of a separate piece of metal for convenience of manipulation, and bolt it to the 70 valve-chamber, as shown in the drawings, a suitable aperture being provided for the purpose. The valve-seat proper is annular, and consists of a ring, H, of rubber or other suitable material, secured between flanges, upon 75 which rests the edge of the hollow cylindrical valve G, operated by lugs or collars i i upon the rod I, which passes loosely through a cross head or bar, g, secured by the valve. The lugs i i are set far enough apart to permit a certain 80 amount of play of the rod in the cross-bar g.

The lower end of the valve-rod I passes loosely through the upper head of the relief-valve V, and is secured by a nut, n.

The valve V is a bottle-shaped piston-valve, 85 fitting and moving in a short cylinder, K, secured in the lower aperture or relief-exit of the chamber, having its upper part or neck provided with guide-wings v to keep it in position when depressed and open.

90

The operation of this portion of my invention is as follows: The valve-rod, in moving upward, at once lifts the waste-valve V to where its cylindrical portion fills and closes the cylinder K, in which it plays. This occurs before the lower lug i of the valve-rod reaches the cross-bar g and lifts the main valve G. As the main valve is then lifted the waste-valve also moves upward, but keeps its aperture closed. In summer weather, when there 100 is no danger of freezing, the waste-valve V is wedged up, so that the packing-ring m upon

its lower flange will form a water-tight joint against the bottom of the valve-seat casting. In this position the valve-rod plays vertically through the waste-valve without hinderance.

5 In my said former invention, to which reference has been made, the vertical column projected downward into the valve-chamber through a suitable stuffing-box, and formed the guide for the valve G, which, therefore, 10 was governed in its movement by the alignment of the pipe A. I now, however, introduce into the top of the valve-chamber a separate casting, C, which forms a socket for the reception and play of the vertical column A. 15 and a guide for the movement of the valve G. This socket C is cylindrical, and provided with an extra flange, f, by means of which it is bolted securely to the top of the chamber F. The lower portion, c', is about the diameter of 20 the vertical column, and is bored interiorly to form a guide for the valve G. Immediately above this portion it is enlarged, as shown at c², to allow for any oscillation or play of the vertical column.

25 At the top of the socket is arranged a stuffing-box formed by the ring D, secured by the flange f' and a rib, r, on the inner surface of the socket near the top. Between these two surfaces is secured a packing-ring, E, of any 30 suitable elastic material.

A leather ring is secured at the lower end of the socket by a ring, D', bolted thereto, thus forming a packing for the valve-guide.

It will be readily seen from this construction 35 and arrangement of parts that the vertical column is independent entirely of the valve, and that neither its vertical play nor any oscillation or defective alignment can affect the seating of the valve.

40 Having fully described my invention, I claim and desire to secure by Letters Patent—

1. In a watering-column of the character described, having a main valve for regulating the supply to the valve-chamber, the combination of a relief-valve having a movement in-

dependent of the main-valve, and mechanism, substantially as described, for operating said relief-valve to close it prior to opening the main valve and independently of the vertical play of the column, as set forth.

2. In a watering-column of the character described, having a main valve for regulating the supply to the valve-chamber, the combination of a relief-valve capable of independent movement from the main valve, and normally 55 standing open, with mechanism, substantially as described, for closing the relief before the main valve is opened and by the act of opening the latter, as set forth.

3. The piston-valve V, constructed as shown, 60 having a neck provided with guide-wings and operating in a cylinder, K, forming the exit-opening, in combination with the main valve-rod, provided with stops i i for the operation of the main valve, substantially as and for the 65 purpose specified.

4. The valve-rod I, provided with stops i i, in combination with the main valve G and relief-valve V, arranged and operating substantially as and for the purpose specified.

5. In combination with the valve-chamber F and vertically-moving pipe A of a watering-column, a socket-piece, C, adapted to be secured to the chamber, forming a guide and stuffing-box for the vertical play of the column 75 and a guide for the supply-valve, substantially as and for the purpose specified.

6. The socket-piece C, constructed as shown, having its lower part bored as a guide-barrel for the reception and play of the main valve, 80 and its upper part arranged to form a stuffing-box for the play of the vertical pipe, and an enlargement between the two to permit lateral oscillation of the vertical pipe.

In testimony whereof I have hereunto set 85 my hand this 22d day of November, 1879.

JOHN N. POAGE.
